Primary Examiner — Michael A. Pratt*Assistant Examiner* — Wendy L Arminio(74) *Attorney, Agent, or Firm* — Carlson, Gaskey & Olds, P.C.(57) **CLAIM**

The ornamental design for a bag closure clip, as shown and described.

DESCRIPTION

FIG. 1 is a perspective view of a bag closure clip according to the present design;

FIG. 2 is an elevational view of the bag closure clip of FIG. 1;

FIG. 3 is a side elevational view of the bag closure clip of FIG. 1;

FIG. 4 is a top view of the bag closure clip of FIG. 1; and, FIG. 5 is a bottom view of the bag closure clip of FIG. 1.
